US0D1057643S

(12) **United States Design Patent** (10) **Patent No.:** **US D1,057,643 S**
(45) **Date of Patent:** **** Jan. 14, 2025**

(54) **POWER STATION**

(71) Applicant: **CEA ELECTRIC CO., LTD**, Fuyang Anhui (CN)

(72) Inventor: **Qilong Tan**, Fuyang (CN)

(73) Assignee: **CEA ELECTRIC CO., LTD**, Fuyang Anhui (CN)

(**) Term: **15 Years**

(21) Appl. No.: **29/855,981**

(22) Filed: **Oct. 10, 2022**

(51) LOC (15) Cl. **13-02**

(52) U.S. Cl.

USPC **D13/103**

(58) **Field of Classification Search**

USPC D13/103, 104, 107, 108, 109, 110, 112, D13/118, 184, 199; D14/432, 434, 356

CPC H02J 7/10; H02J 7/027; H02J 7/0042

(57) **CLAIM**

The ornamental design for a power station, as shown and described.

DESCRIPTION

FIG. 1 is a front and top perspective view of a power station, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures illustrate portions of the power station that form no part of the claimed design.

1 Claim, 8 Drawing Sheets
